ATTORNEYS.

UNITED STATES PATENT OFFICE

ALBERTO BOSCH, OF HABANA, CUBA

ANCHOR FOR BOATS

Application filed September 21, 1931, Serial No. 564,213, and in Cuba January 29, 1931.

This invention relates to improvements in anchors and has for its object to provide an improved construction which will afford a high degree of security when the anchor is lowered into position and which, when tension is applied to the attaching cable, will quickly and effectually release itself from objects engaged therewith and thus facilitate the lifting of the anchor.

10 In the accompanying drawing wherein an approved embodiment of the invention is illustrated:

Fig. 1 is an edge elevation of the improved anchor.

15 Fig. 2 is a top plan view thereof.

Fig. 3 is a perspective view of the body of the anchor, the attaching ring thereof being removed.

20 Fig. 4 is a detail plan view of the attaching ring and rod removed from the body of the anchor.

Figs. 5, 6, 7 and 8 are views illustrating the various positions of the anchor during lifting thereof.

25 Referring to the drawing in detail, the body of the anchor is indicated at 1 and throughout the major portion of its length it is flat. One end of the body is rounded and the opposite end thereof is formed with

30 a slit, the portions at the opposite sides of the slit being turned outwardly and pointed to form two oppositely curved tongues 4. The rounded end of the body 1 is formed with a marginal rib 1b which extends along

35 the two sides thereof to a point adjacent the base of the tongues 4 so as to prevent the anchor from lying upon its edge on the sea bottom. The portions of the body lying above and below the rib 1b are recessed as

40 indicated at 1d to aid in preventing the anchor from slipping.

At a point adjacent the inner extremities of the tongues 4, the body 1 is provided with recesses 1a receiving the inturned ends 45 2a of the attaching ring 2. The recesses 1a are arranged in relatively close relation to the extremity of the body carrying the tongues 4 so that when suspended by the ring 2 the anchor body assumes an upright position with the tongues 4 uppermost. The rel-

atively wide base portions 1c of the tongues coact with the adjacent substantially parallel portions 2b of the ring to normally maintain the latter in a position between the two tongues 4 as indicated in Figs. 1 and 2. By 55 swinging the ring in either direction the parallel side portions 2b thereof are sprung in passing over the base portions 1c and resume their normal position when the ring has been swung to the positions shown in Figs. 7 and 8.

A rod 3 is pivotally mounted intermediate its ends on the medial portion of the ring 2, as indicated at 3b, and is attached at one end to a cable 5. The opposite extremity of 65 the rod 3, which is grooved at 3a, normally occupies a position between the pointed extremities of the tongues 4 and further aids in maintaining the ring 2 in proper position with respect to the tongues 4.

In lowering the anchor to operative position it is suspended from the cable 5 in an upright position with the tongues 4 uppermost, and upon reaching the bottom it assumes the position shown in Fig. 5. In the 75 act of lifting the anchor, a pull is exerted on the cable 5 and the vessel to which the anchor is attached is brought into approximate position shown in Fig. 6. By continuing the pull on the cable 5, the ring 2 is 80 expanded in passing over the base portions 1c of the tongues and moves from the position shown in Fig. 6 to that shown in Fig. 7. As the tension on the cable is increased the body is swung upwardly with one of the 85 anchoring tongues 4 as a fulcrum to the position shown in Fig. 8 in which the tongues are freed, and by continuing the upward pull on the cable, the anchor may be completely raised.

90 I claim:

1. An anchor comprising a flat body slit at one end to define anchoring tongues, the two tongues being curved outwardly in opposite directions and projecting laterally 95 beyond the flat sides of the body, and a supporting ring pivotally attached to the body at a point adjacent the slit end whereby the weight of the opposite end of the body tilts the latter to a vertical position 100

with the tongues disposed uppermost when the body is held suspended from said ring.

2. An anchor comprising a flat body slit at one end to define anchoring tongues, the two tongues being curved outwardly in opposite directions and projecting laterally beyond the flat sides of the body, and a supporting ring pivotally attached to the body at a point adjacent the slit end whereby the weight of the opposite end of the body tilts the latter to a vertical position with the tongues disposed uppermost when the body is held suspended from said ring, said tongues having such width at the base portions thereof as to normally confine the ring in position between the tongues.
3. An anchor comprising a flat body slit at one end to define anchoring tongues, the two tongues being curved outwardly in opposite directions and projecting laterally beyond the flat sides of the body, and a supporting ring pivotally attached to the body at a point adjacent the slit end whereby the weight of the opposite end of the body tilts the latter to a vertical position with the tongues disposed uppermost when the body is held suspended from said ring, said tongues having such width at the base portions thereof as to normally confine the ring in position between the tongues and permitting the ring to swing to a position substantially perpendicular to the body upon application of sufficient force to the ring to cause the latter to move past the base portions of the tongues.

4. An anchor comprising a flat body slit at one end to define anchoring tongues, the two tongues being curved outwardly in opposite directions and projecting laterally beyond the flat sides of the body, a supporting ring pivotally attached to the body at a point adjacent the slit end whereby the weight of the opposite end of the body tilts the latter to a vertical position with the tongues disposed uppermost when the body is held suspended from said ring, and a rod pivotally mounted intermediate its ends on the medial portion of the ring and, during the use of the anchor, occupying a position between the tongues.

ALBERTO BOSCH.
